[57] CLAIM

The ornamental design for a floor lamp, as shown and described.

DESCRIPTION

FIG. 1 is a perspective view of a floor lamp showing our new design;

FIG. 2 is a side elevational view thereof;

FIG. 3 is a top plan view thereof;

FIG. 4 is an enlarged, fragmentary side elevational view of the section of the standard shown within circle 4 in FIG. 2;

FIG. 5 is an enlarged fragmentary side elevational view of the base of the standard shown within circle 5 in FIG. 2;

FIG. 6 is a perspective view of a second embodiment of our new design;

FIG. 7 is a side elevational view thereof as seen from the right of FIG. 6; and,

FIG. 8 is a top plan view thereof.
